UNITED STATES PATENT OFFICE.

ABIEL BETEL REVELLI, OF TURIN, ITALY.

BALL-AND-SOCKET JOINT FOR MOUNTING FIREARMS ON SHIELDS, PARAPETS, AND THE LIKE.

1,241,149.

Specification of Letters Patent. Patented Sept. 25, 1917.

Application filed October 16, 1916. Serial No. 126,006.

To all whom it may concern:

Be it known that I, ABIEL BETEL REVELLI, colonel in the Italian army, and a subject of the King of Italy, residing at 57 Corso Duca di Genova, Turin, Italy, have invented certain new and useful Improvements in Ball-and-Socket Joints for Mounting Firearms on Shields, Parapets, and the like; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention refers to a ball and socket joint for mounting firearms on shields, parapets and the like, whereby the firearm can be freely moved within the practically useful arc of fire for the purpose of sighting.

In the annexed drawings I have shown, by way of example, a constructional form of the present device applied to a shield.

Figure 1 is a front view thereof;

Fig. 2 is a cross section on line A, A, Fig. 1;

Fig. 3 illustrates the central plate on which the firearm is secured: the upper left hand side view being a side elevation, the upper right hand side view a front elevation, and the lower view a top view thereof;

Fig. 4 is a section, on line B, B of Fig. 1, of the shield;

Fig. 5 is a vertical section on line S, S of Fig. 4.

The shield 1 is provided with an opening 2 (Figs. 4 and 5), the inner surface of which is in form of a spherical zone of the spherical surface 3 (Fig. 2) having its center at 4.

On two opposite sides 5, each measuring something less than $\frac{1}{4}$ the circumference, the spherical zone of the opening 2 is made cylindrical with a diameter equal to that of the spherical surface, in order to allow a free passage of the central plate 6 through which the barrel 7 of the firearm is introduced and secured. The two opposite cylindrical parts of the inner surface of the opening 2 may suitably extend (as in the constructional form of Fig. 4) only on one half the thickness of the shield 1; the other

half being kept spherical to retain the plate, when this latter is being introduced in the shield, in its only exact position, in which its two spherical surfaces 8 may rotate in the corresponding spherical cavities of the shield 1. The two opposite sides 8 of the plate 6 are equal to about $\frac{1}{4}$ of the circumference and have the form of a spherical zone corresponding to that of the opening 2 on which they may slide with soft friction, while the two intermediate sides 9 are cylindrical, their diameter being slightly smaller than the shortest diameter of the spherical zone.

It is evident that the plate 6 may be introduced in the opening 2 of the shield (Fig. 5) in the position shown in Fig. 3; whereupon by causing it to rotate through 90° on an axis perpendicular to the shield, the two spherical surfaces will lie on one another (Figs. 1 and 2) and therefore the plate 6 (and with it the firearm secured thereto) will be allowed to move freely in all directions about the center 4 for sighting and aiming the arm without any risk of becoming detached from the shield. The opening 10 provided in the shield 1 allows to find out the sighting line.

What I claim is:

1. In a socket and ball joint for mounting firearms on shields, parapets and the like, an opening provided in these latter in form of a spherical zone and cut in a number of parts to allow the introduction of a plate also in form of a spherical zone and cut in a corresponding number of parts, the two surfaces in form of spherical zone sliding on one another with a soft friction.

2. In a socket and ball joint for mounting firearms on a support, an opening provided in the support, the inner surface of which is in form of a spherical zone having two cylindrical portions of the same diameter as the spherical zone, said portions measuring less than $\frac{1}{4}$ the circumference of said zone and extending suitably on one half of the thickness of the shield,—a central plate on which is secured the barrel of the firearm, two opposite sides of which have the form of a spherical zone corresponding to that of the opening, while the intermediate sides are cylindrical and of a diameter slightly

smaller than the shortest diameter of the spherical zone, in order to allow its introduction in the shield opening when in the right position and to secure it in place by 5 means of a rotation of 90°, thus allowing the sighting in all directions through displacement about the center of the spherical surface.

In testimony that I claim the foregoing as my invention, I have signed my name in 10 presence of two subscribing witnesses.

ABIEL BETEL REVELLI.

Witnesses:

JACOHECCI FERRUCCIO,
NORAH WHITESTONE.
